CONSTANT SPEED CONTROL FOR MOTORS

Paul U. Lannerd, Elyria, Ohio, assignor to The General Industries Company, Elyria, Ohio, a corporation of Ohio

Application July 21, 1937, Serial No. 154,796

14 Claims. (Cl. 188—187)

This invention relates to electric motors of the rotor type, wherein suitable means are provided for maintaining the R. P. M. or speed of the rotor substantially constant, regardless of current fluctuations and particularly that type adaptable for use in phonographs or similar reproducing apparatus.

In the type of motor referred to, a governor is employed which is operatively connected to the rotor and rotatable therewith. The governor has a metal disc axially movable into and out of engagement with a fixed abutment, usually of felt or other suitable material, and which, after a short period of time, becomes carbonized because of improper lubrication and its repeated engagement with the rotating disc. Under this condition, the frictional resistance between the disc and abutment varies and as a result thereof, the speed of the rotor is not maintained constant as desired. Furthermore this hardening of the felt abutment has the effect of setting up vibrations which causes chattering of the disc and other objectionable noises. It is therefore, an object of the present invention to provide means for substantially continuously lubricating the felt abutment, regardless of the otherwise required lubrication thereof, thus eliminating the objectionable consequences heretofore referred to.

A further object of the invention is to provide a means of lubrication which is simple in construction, efficient in purpose and inexpensive to embody.

With the objects above indicated and other objects hereinafter explained, in view, my invention consists in the construction and combination of elements hereinafter described and claimed.

Referring to the drawing,

Figure 1 is a side elevational view of a motor with the device embodying the present invention attached thereto.

Figure 2 is a side elevational view of the speed control mechanism showing the elements in spaced relation axially and representing their manner of assembly.

Figure 3 is a front view of the lubricant receptacle constituting one element of the present invention.

Figure 4 is a side elevational view of that shown in Figure 3.

Figure 5 is an end elevational view of the governor utilized in the present instance and shown in side elevation in Figures 1 and 2.

In the drawing I have illustrated a motor of the type employed in phonographs or similar reproducing apparatus and having attached

thereto one type of speed control mechanism embodying the present invention but it should be understood that the invention is as readily adaptable to other uses and is not, therefore, to be so restricted.

The motor is indicated generally by the numeral 10 and may be of various types. In the present illustration it comprises a skeleton housing 11, preferably of cast metal, which includes a bridging portion 12 providing an attaching surface by means of which the motor 10 may be readily mounted in the cabinet or other supporting structure. At the opposite ends of the bridging portion 12, as viewed in Figure 1, are depending extensions 13 and 14 preferably formed integral therewith and which extend relatively in parallel spaced relation.

At the end of the housing 11 adjacent the extension 14 a field magnet and yoke 15 is disposed and is suitably connected thereto. Magnetizing coils 16, only one of which is shown, are mounted on opposite sides of the field magnet 15 and are mechanically and electrically connected thereto. An armature 17 is rotatably disposed within the field magnet and yoke 15 and between the magnetizing coils 16. Inasmuch as the foregoing general description is well known to those skilled in the art it is not believed necessary to elaborate further in view of the fact that the motor structure does not enter into the inventive subject matter of the present application and that other types may be employed.

The armature 17 has a shaft 18 which projects axially thereof and is rotatably mounted in suitable aligned bearings provided in the extensions 13 and 14. The end of the armature 17, opposite the shaft 18, abuts an adjusting screw 19 adjustably mounted in a bridging member 20, the opposite ends of which are secured to the adjacent sides of the field magnet and yoke. This adjusting screw functions as a thrust bearing for the armature and additionally positions and maintains the armature in its proper relation with respect to the yoke. The shaft 18, between its bearings, is provided with a worm 21 which is in constant mesh with a pinion 22 secured to a shaft 23 which extends at right angles to the axis of the shaft 18, and is journaled for rotation in suitable aligned bearings provided in the bridging portion 12 and a plate 24. This plate 24 extends in parallelism with respect to the bridging portion 12 and has its opposite ends detachably connected to the free ends of the extensions 13 and 14. One end of the shaft 23 projects outwardly beyond the bridging portion 12 and has a reduced 55

end 25 to permit ready mounting of a record thereover in the usual manner and a transversely extending pin 26 adjacent the bridging portion 12 provides a rest or stop for the record. By reason 5 of the gear arrangement rotation of the motor shaft 18 imparts rotation to the record shaft 23 and as the record is secured on the latter is rotatable therewith.

It is important that the record be rotated continuously and at a constant speed or R. P. M. in order that the recorded material be properly reproduced. Principally because of current fluctuations the speed or R. P. M. of the motor shaft varies and in order to overcome this condition a speed control mechanism is employed. Any suitable type may be selected, but preferably, as illustrated, the governor type is used. The end of the shaft 18 projects beyond its bearing in the extension 13 and a governor 27 is mounted thereon. The governor comprises a sleeve formed of coaxially aligned sections 28 and 29 which are slidably mounted on the free end shaft 18. The section 28 has a set screw 30 for securing that section against relative movement with respect to the shaft 18 but the section 29 is free to slide therealong. The adjacent ends of the sections 28 and 29 have connecting grooves and extensions of complementary shape and function as cam means for moving the section 29 axially with respect to the section 28 in a manner to be later described.

The section 28 has oppositely extending tapered arms 31 and 32 the outer ends of which are positioned on opposite sides of a vertical plane passing through the axis of the shaft 18 as viewed in Figure 5. The section 29 has similar oppositely extending tapered arms 33 and 34 the outer ends of which are positioned on opposite sides of the same vertical plane, the adjacent ends of the arms, however, being positioned relatively on opposite sides of the central plane as viewed in Figure 5. Weight members 35 and 36 are disposed on opposite sides of the arms adjacent the axis of the shaft 18 and at right angles with respect to the vertical axis before referred to and have resilient bands 37 and 38 connected at their mid portions with the inner sides of the weight members 35 and 36 respectively. The opposite ends of the band 37 extend angularly and has one end connected to the outer end of the arm 33 and its other end connected to the outer end of the arm 32 diametrically opposite. The opposite ends of the band 38 likewise extend angularly and the band has one end connected to the outer end of the arm 31 and its other end connected to the outer end of the arm 34 diametrically opposite. It will be seen, therefore, that upon rotation of the shaft 18 the weight members, due to centrifugal force, will tend to move apart relatively and through the linkage described will cause the section 29 to move axially and away from the section 28. As the speed of the shaft is reduced the section 29 will move axially toward the section 28.

The section 29 has a circular disc 39 secured thereto and adapted for movement therewith. The disc has a flat inner surface 40 and a tapered marginal edge 41 to provide a feathered edge at the inner surface for a purpose to be later described. An abutting member 42 of felt or other suitable material, has one end secured within a holder 43 which in turn is slidably mounted within an opening 44 in the adjacent end of the extension 13, Fig. 2. The opposite end of the holder is tapered and provided with a recess 45

which extends longitudinally thereof and is adapted to receive the end 46 of an adjusting screw 47 screwthreadedly mounted in the bridging portion 12. This provides a means for proper positioning of the holder 45 and by adjusting the screw 47 the outer end of the abutting member 42 may be positively positioned for frictional engagement with respect to the adjacent surface of the disc 39. When the current to the motor is turned on, the shaft 18 is rotated freely and by turning the adjusting screw 47 in one direction the holder 43 will be moved axially outwardly until the felt abutting member 42 contacts with the adjacent surface of the rotating disc 39. The amount of frictional resistance offered is determinate of the speed or R. P. M. of the shaft 18 and when once adjusted very little attention is further required, the action being automatic thereafter except for possible wear. If the current fluctuates, the weight members 35 and 36 respond in a manner to either move the disc 39 more forcefully against the felt abutment 42 which compensates for the variance and maintains the desired constant R. P. M., or away from the felt abutment 42 which lessens the frictional resistance and thus maintains the R. P. M. constant. The free end of the shaft 18 projects slightly beyond the section 28 of the governor 27 and abuts a thrust bearing 51 adjustably mounted in the end of a U shaped bracket 58. By adjusting the bearing the shaft 18 is positively positioned so as to maintain the armature 17 in proper relation with respect to the magnetic yoke 15. The free ends of the bracket 58 are detachably connected to the housing by means of bolts 59. This much of the description relates to one type of motor equipped with a speed control mechanism of the governor type and forms no part of the present invention except as it may be incorporated in combination therewith.

Ordinarily a suitable opening is provided in the housing or elsewhere whereby a suitable lubricant may be manually introduced periodically to keep the felt abutting member 42 properly lubricated. However, as is well known when the oiling is left to individual attention it is frequently overlooked or disregarded entirely. Under this circumstance the continuous rotation of the disc 39 and its contact with the relatively stationary felt abutting member 42 causes the contacting end of the latter to become carbonized thus presenting a hard non-resistable surface which does not react properly to current fluctuations and which causes a chattering of the disc as well as other objectionable noises.

To eliminate or correct these objectionable consequences, I provide a means of lubricating the felt abutting member 42 and further a supply of lubricant which is continuously applied. Obviously this may be accomplished in a number of ways but preferably, as illustrated in the drawing, comprises a receptacle 48 of circular form provided with an inturned tapered marginal flange 49, the opening defined by the free edge of the flange being just large enough to permit free movement of the disc 39 therethrough when properly mounted as shown in Figure 1. A pad of absorbent material 50 such as felt, is placed within the receptacle 48 and small headed brads 51 secure the pad within the receptacle and the receptacle to the outer side of the extension 13 as shown in Figure 1. Thin washers 52 are disposed between the heads of the brads and the pad to prevent the heads from being driven entirely through the pad as the receptacle is secured

to the housing. As viewed in Figure 3, it will be seen that two openings are provided for the brads on diametrically opposite sides of the receptacle and offset slightly from the axis thereof and that an opening 53 is provided to permit the end of the holder 43 to project therethrough so as not to interfere with the adjustability thereof. An axial opening 54 is also provided through which the motor shaft 18 freely passes.

10 The felt pad 59 likewise has an axial opening 55 to accommodate the shaft 18 and an opening 56 through which the end of the felt abutting member 42 snugly projects. This pad 59 is saturated with oil or other suitable lubricant and 15 being constantly in contact with the end of the felt abutting member 42 supplies the necessary amount of lubricant by capillary action to the abutting member thus maintaining it in proper condition. The oil which is transferred to the 20 contacting surface 49 of the disc 39 is thrown outwardly due to the rotation of the disc and the feathered edge causes the oil to be discharged where it strikes the inner flanged surface of the receptacle and is again absorbed by the pad. This 25 saves a great proportion of the oil for reuse and as a result materially increases the length of service. Additionally, dust to a great extent is prevented from coming into contact with the under side of the disc adjacent the abutting member due to the enclosing relation of the receptacle. The collection of dust on the abutting member heretofore was one of the primary reasons for the carbonizing result.

While I have described the preferred embodiment of the invention it is to be understood that I am not to be limited thereto inasmuch as changes and modifications may be resorted to without departing from the spirit of the invention as defined in the appended claims.

30 40 What is claimed is:

1. In combination a motor having a shaft rotatably mounted in the housing thereof, and a speed control mechanism including a governor mounted on said shaft and rotatable therewith, a disc operatively connected to said governor for rotation therewith but movable axially relatively thereto under the influence of said governor, a felt abutment adjustably mounted in said motor housing and having a projecting end engageable 45 with said disc for frictionally retarding its rotation, a lubricant absorbent means on said housing and in contact with the projecting end of said felt abutment for substantially continuously supplying lubricant thereto, and means 50 for collecting and returning the spent lubricant to said lubricant absorbent means.

2. In combination a motor having a shaft rotatably mounted in the housing thereof, and a speed control mechanism including a governor mounted on said shaft and rotatable therewith, a disc operatively connected to said governor for rotation therewith but movable axially relatively thereto under the influence of said governor, a felt abutment adjustably mounted in said motor housing and having a projecting end engageable 55 with said disc for frictionally retarding its rotation, a lubricant receptacle connected to said motor housing, and a lubricant absorbent pad in said receptacle in contact with said felt abutment for substantially continuously supplying a lubricant to the latter.

3. In combination a motor having a shaft rotatably mounted in the housing thereof, and a speed control mechanism including a governor mounted on said shaft and rotatable therewith,

a disc operatively connected to said governor for rotation therewith but movable axially relatively thereto under the influence of said governor, a felt abutment adjustably mounted in said motor housing and having a projecting end engageable 5 with said disc for frictionally retarding its rotation, a lubricant receptacle connected to said motor housing and having a portion in enclosing relation with respect to said disc, and a lubricant absorbent pad in said receptacle in contact with 10 said felt abutment for substantially continuously supplying a lubricant to the latter.

4. In combination a motor having a shaft rotatably mounted in the housing thereof, and a speed control mechanism including a governor 15 mounted on said shaft and rotatable therewith, a disc operatively connected to said governor for rotation therewith but movable axially relatively thereto under the influence of said governor, said disc having a beveled marginal edge tapering 20 toward the governor, a felt abutment adjustably mounted in said motor housing and having a projecting end engageable with said disc for frictionally retarding its rotation, a lubricant receptacle connected to said motor housing and having a marginal wall projecting beyond the beveled edge of said disc in enclosing relation thereto, and a lubricant absorbent pad in said receptacle 25 in contact with said felt abutment for substantially continuously supplying a lubricant to the 30 latter.

5. In combination a motor having a shaft rotatably mounted in the housing thereof, and a speed control mechanism including a governor mounted on said shaft and rotatable therewith, 35 a disc operatively connected to said governor for rotation therewith but movable axially relatively thereto under the influence of said governor, a felt abutment adjustably mounted in said motor housing and having a projecting end engageable 40 with said disc for frictionally retarding its rotation, a lubricant receptacle having a shaft opening and an abutment opening, a lubricant absorbent pad in said receptacle in contact with said felt abutment for substantially continuously 45 supplying a lubricant to the latter, and means for securing said pad to said receptacle and the latter to said motor housing.

6. In combination a motor having a shaft rotatably mounted in the housing thereof, and a speed control mechanism including a disc operatively connected to said shaft for rotation therewith but movable axially relatively thereto, a felt abutment adjustably mounted in said motor housing and having a projecting end engageable 55 with said disc for frictionally retarding its rotation, a lubricant absorbent means on said housing and in contact with the projecting end of said felt abutment for substantially continuously 60 supplying lubricant thereto, and means for collecting and returning the spent lubricant to said lubricant absorbent means.

7. In combination a motor having a shaft rotatably mounted in the housing thereof, and a speed control mechanism including a disc operatively connected to said shaft for rotation therewith but movable axially relatively thereto, a felt abutment adjustably mounted in said motor housing and having a projecting end engageable 70 with said disc for frictionally retarding its rotation, a lubricant receptacle connected to said motor housing, and a lubricant absorbent pad in said receptacle in contact with said felt abutment for substantially continuously supplying a lubricant to the latter.

8. In combination a motor having a shaft rotatably mounted in the housing thereof, and a speed control mechanism including a disc operatively connected to said shaft for rotation therewith but movable axially relatively thereto, a felt abutment adjustably mounted in said motor housing and having a projecting end engageable with said disc for frictionally retarding its rotation, a lubricant receptacle connected to said motor housing and having a portion in enclosing relation with respect to said disc, and a lubricant absorbent pad in said receptacle in contact with said felt abutment for substantially continuously supplying a lubricant to the latter. 5
- 10 9. In combination a motor having a shaft rotatably mounted in the housing thereof, and a speed control mechanism including a disc operatively connected to said shaft for rotation therewith but movable axially relatively thereto, said disc having a beveled marginal edge tapering outwardly, a felt abutment adjustably mounted in said motor housing and having a projecting end engageable with said disc for frictionally retarding its rotation, a lubricant receptacle connected to said motor housing and having a marginal wall projecting beyond the beveled edge of said disc in enclosing relation thereto, and a lubricant absorbent pad in said receptacle in contact with said felt abutment for substantially continuously supplying a lubricant to the latter. 15
- 20 10. In combination a motor having a shaft rotatably mounted in the housing thereof, and a speed control mechanism including a disc operatively connected to said shaft for rotation therewith but movable axially relatively thereto, an adjustably mounted abutting member of lubricant absorbing and retaining material engageable with said disc for frictionally retarding its rotation, a lubricant receptacle connected to said motor housing and having a portion in enclosing relation with respect to said disc, and a lubricant absorbent pad in said receptacle in contact with said abutting member for substantially continuously supplying a lubricant to the latter. 20
- 25 11. In combination a motor having a shaft rotatably mounted in the housing thereof, and a speed control mechanism including a disc operatively connected to said shaft for rotation therewith but movable axially relatively thereto, an adjustably mounted abutting member of lubricant absorbing and retaining material engageable with said disc for frictionally retarding its rotation, a lubricant receptacle connected to said motor housing and having a marginal wall projecting beyond the beveled edge of said disc in enclosing relation thereto, and a lubricant absorbent pad in said receptacle in contact with said felt abutment for substantially continuously supplying a lubricant to the latter. 25
- 30 12. In combination a motor having a shaft rotatably mounted in the housing thereof, and a speed control mechanism including a disc operatively connected to said shaft for rotation therewith but movable axially relatively thereto, an adjustably mounted abutting member of lubricant absorbing and retaining material engageable with said disc for frictionally retarding its rotation, a lubricant receptacle connected to said motor housing and having a portion in enclosing relation with respect to said disc, and a lubricant absorbent pad in said receptacle in contact with said abutting member for substantially continuously supplying a lubricant to the latter. 30
- 35 13. In combination a motor having a shaft rotatably mounted in the housing thereof, and a speed control mechanism including relatively movable and stationary abutting members, one of said members being formed of a lubricant absorbing and retaining material, the movable member being operatively connected to said rotatable shaft, a lubricant absorbent means on said housing and in contact with said member of lubricant absorbing and retaining material for substantially continuously supplying lubricant thereto, and means for collecting and returning the spent lubricant to said lubricant absorbent 35 means. 35
- 40 14. In a speed control mechanism for a rotatable shaft, relatively movable and stationary abutting members, one of said members being formed of a lubricant absorbing and retaining material, said movable member being adapted for operative connection with the rotatable shaft, a lubricant absorbent means in contact with said member of lubricant absorbing and retaining material for substantially continuously supplying lubricant thereto, and means for collecting and returning the spent lubricant to said lubricant absorbent means. 40
- 45 15. In combination a motor having a shaft rotatably mounted in the housing thereof, and a speed control mechanism including a disc operatively connected to said shaft for rotation therewith but movable axially relatively thereto, an
